UNITED STATES PATENT OFFICE.

CHARLES T. GROSJEAN, OF NEW YORK, N. Y., ASSIGNOR TO TIFFANY & CO., OF SAME PLACE.

DESIGN FOR A SPOON-HANDLE.

SPECIFICATION forming part of Design No. 15,831, dated February 17, 1885.

Application filed December 31, 1884. Term of patent 14 years.

To all whom it may concern:

Be it known that I, CHARLES T. GROSJEAN, a citizen of the United States, residing in the city, county, and State of New York, have invented and produced a new and original Design for a Spoon-Handle or other Article of Table-Service, of which the following is a specification, reference being had to the accompanying drawings, forming part thereof.

10 The design for this spoon-handle consists in the statuette of a North American Indian, with the ornamental decoration as exhibited on the blanket, basket, tent, paddle, head, and feather-work, &c., of same. The statuette of the Indian is placed in the head of the spoon at the top of the shank. In the several spoons composing the set the statuette is represented as in the various war-dances.

15 In the drawings, Figures 1 to 12, inclusive, are front views of the handles, representing the statuette in and clothing and equipment for twelve games, dances, &c. Figs. 13 to 24, inclusive, are views of the reverse sides of said handles shown in Figs. 1 to 12. Fig. 1 20 represents a front view of the statuette as a full-dressed warrior. Fig. 13 is a rear view thereof. Fig. 2 represents a front view of the statuette as a lacrosse player. Fig. 14 is a rear view thereof. Fig. 3 represents a front 25 view of the statuette as an Indian maid. Fig.

15 is a rear view thereof. Fig. 4 represents a front view of the statuette in the bear-dance. Fig. 16 is a rear view thereof. Fig. 5 represents a front view of the statuette in the war-dance. Fig. 17 is a rear view thereof. Fig. 35 30 6 represents a front view of the statuette in the buffalo-dance. Fig. 18 is a rear view thereof. Fig. 7 represents a front view of the statuette in the pipe-dance. Fig. 19 is a rear view thereof. Fig. 8 represents a front view of the statuette in the bow-dance. Fig. 20 is a rear view thereof. Fig. 9 represents a front view of the statuette in the club-dance. Fig. 21 is a rear view thereof. Fig. 10 represents a front view of the statuette in the discovery-dance. Fig. 45 40 Fig. 22 is a rear view thereof. Fig. 11 represents a front view of the statuette in the medicine-dance. Fig. 23 is a rear view thereof. Fig. 12 represents a front view of the statuette in the coyote-dance. Fig. 24 is a 50 rear view thereof.

I claim—

The design for a spoon-handle, containing in the head thereof at the top of the shank the statuette of an Indian, substantially as described and shown.

CHARLES T. GROSJEAN.
